NET LINER

Blanche Neaves, Missoula, Mont.

Application September 24, 1936, Serial No. 102,406

3 Claims. (Cl. 132—1)

This invention relates to a sanitary band adapted to be placed between the forehead of the wearer and the elastic border of a hair net.

The object of this invention is to provide a sanitary band for use in beauty parlors that can be placed against the forehead of a customer to protect the forehead from the imprint of the elastic border of a hair net used by the operator to hold the customer's hair in position during drying and after curling.

Another object of the invention is to produce the band of such inexpensive material that it may be discarded after each use, so that each customer will have the advantages of the sanitary precautions accompanying the use of the band.

Other objects and advantages of the invention will become apparent from the drawing and the description to follow.

In the drawing:—

20 Figure 1 is a side elevation showing the band and hair net in position on a figurehead;

Figure 2 is a fragmentary sectional view of a portion of the band with a hair net applied thereto;

25 Figure 3 is a front elevation of the band folded and ready for use;

Figure 4 is an elevational view showing the band in open position;

Figure 5 is a view similar to Figure 4 of a modified form of band;

Figure 6 is a view similar to Figure 3 of the modified form of band, and

Figure 7 is a cross section on the line 7—7 of Figure 6.

30 Referring more particularly to the drawing wherein like reference characters designate like or corresponding parts in the different views, 10 is the sanitary band preferably composed of several superposed strips or layers of thin tissue paper or the like as best shown in Figure 2.

The band 10 is folded lengthwise to form the two portions 11 and 12. The wider portion 11 is adapted to rest against the forehead of the wearer when in use as shown in Figure 1.

45 A hair net 13, having an elastic strip 14 secured to its edge, is adapted to fit in the fold and hold the band 10 in position upon the head of the user as shown in Figure 2.

Figures 5, 6 and 7 show a modified form of band, the band 15 in the modification being folded to form the portions 16 and 17. The portions 16 and 17 are provided with tongues 18 and 19 formed by cutting the material on three sides and bending the intermediate material outwardly of the body of the band to engage portions of the hair net to prevent it from slipping out of position on the band 15.

The portions 12 and 17 are folded upward to prevent the bands 10 and 15 from slipping up under the hair net 13 and exposing the forehead of the wearer to the pressure of the elastic 14 and thereby causing an imprint on the forehead of the wearer.

It is to be understood that only the preferred embodiment of the invention has been shown, the right being reserved to make such changes and modifications as will not depart from the spirit and scope of the invention.

I claim:—

1. A removable band for hair nets, comprising a strip of laminated material folded lengthwise, cut-out portions in the opposite sides of the fold forming tongues, and said tongues serving to hold a hair net in position in the fold of said band.

2. A sanitary band for hair nets comprising a strip of laminated material folded lengthwise, cut-out portions in the opposite sides of the fold forming tongues, said tongues being turned inwardly toward each other, and adapted to cooperate to hold the hair net in position in said fold.

3. A removable sanitary protector for hair nets comprising a strip of material folded lengthwise and adapted to receive the elastic band of the hair net in said fold, and cut-out portions in the opposite sides of said strip forming tongues, said tongues projecting inwardly and downwardly to cooperate with the fold to retain the elastic band therein, said strip adapted to rest against the forehead of the user to protect it from the pressure of the elastic band.

BLANCHE NEAVES. 45
